Elmer J. Key, of Lowell, Mass.
Assignor to
The Lowell Manufacturing Company.
Letter Patent No 1724, dated Mar. 3, 1863.

The schedule referred to in these Letters Patent and making part of the same

To all whom it may concern:

Be it known that I, Elmer J. Key, of Lowell, in the County of Middlesex and State of Massachusetts, now temporarily residing in New York, have originated and designed a new pattern for carpets or other fabrics, of which the following is a full, clear, and exact description, reference being had to the accompanying drawings, making part of this specification.

In corner 1, is one fourth of a small star resting on the ground A, which is enclosed by a frame composed of the solid scrolls 3, 3, leaves 4, 4, and rosettes 5.

The figures and surroundings of corner 2, are similar to those of corner 1.

In corner 6, is one fourth of a large rosette, resting on the plain ground B, which is enclosed by the frame of scrolls 8. In corner 7, are figures similar to those of corner 6. On the centre is a sprig which rests on a plain ground surrounded by a wreath of leaves 9.

The remainder of the design consists of a diamond ground work, supporting heavy bars which run across the design.

The colors employed for the different portions of the design, may be varied to suit the taste and wish of the manufacturer.

Claim

What I claim as my invention, and desire to secure by letters patent, is the design, or pattern, for carpets or other fabrics herein set forth.
